SAFETY CONTROL MECHANISM

Robert A. Dornbos, Chicago, and John D. Feeney,
 Downers Grove, Ill., assignors to Western Electric Company, Incorporated, New York, N. Y., a corporation of New York

Application April 1, 1949, Serial No. 84,944

3 Claims. (Cl. 175—320)

1

This invention relates to control mechanism and more particularly to a two-button microswitch control for power presses and like machinery.

In the operation of power presses and similar machinery, it is desirable that maximum operator safety be maintained at all times. It is known in the art to provide two switch or two button control devices and circuits for initiating the operation of power machinery. Controls of this type usually have their two switches located at such a distance from each other that it is necessary for the operator to use both hands to control the two switches. It has been found, however, that most control circuits of this type are designed in such a way that it is possible for the operator to tie or "stake" one of the control switches in the closed position, thereby giving him control over the machinery by merely depressing or closing one switch. In this case, maximum operator safety is not maintained since he has one free hand which might easily be caught in the machinery during its operating cycle.

It is an object of this invention to provide a two-button manual circuit control wherein it is absolutely necessary that both buttons be depressed and immediately released to initiate an operating cycle of the machinery under control.

In accordance with one embodiment of the invention, a two-button circuit control device is provided for controlling a power press or like machine wherein a cycle of operation of the press is initiated by the energization of a solenoid which retracts an armature type clutch trip. Upon retraction of the clutch trip, the punch press is driven through one cycle of operation through, for example, a well-known type one-revolution clutch. The control circuit includes two manually operated switches which, when closed, energize a normally open relay and a slow-to-operate normally closed relay and the circuit arrangement is such that the clutch trip is not actuated unless both switches are released before the slow-to-operate relay has opened its contacts. It will thus be seen that any attempt to tie or "stake" down one of the switches will render the circuit inoperative and it will further be observed that when both switches are released properly, the cycle of operation will take place before the operator can move his hands from the switches to the danger area beneath the press.

Other objects and advantages will more fully appear from the following detailed description

2

when read in conjunction with the accompanying drawings wherein:

Fig. 1 is a partial diagrammatic view of a power press using the invention, and

Fig. 2 is a schematic circuit diagram of one embodiment of the invention.

Referring now to Fig. 1, a punch press, indicated generally at 10, is driven by a source of power (not shown) through a conventional one-revolution type clutch 11. One cycle of operation of the punch press 10 is initiated by retraction of an armature type clutch trip 12, which is retractable into a solenoid 13. The solenoid 13 is energized by means of a control circuit, shown in block form at 14 (Fig. 1), and shown in detail in Fig. 2. The cycle of operation is initiated by depressing and immediately releasing a pair of manually controlled switches 15, only one of which is shown in Fig. 1.

Referring now to Fig. 2, a control circuit, indicated generally at 14, comprises two single pole double throw switches 15 having A and B contacts which alternately connect the solenoid 13 and control circuit 14 to a source of alternating current 16. A relay 17, having normally open contacts 18, 19 and 20, has its operating coil connected in series with the source of current 16 through the B contacts of switches 15 and a slow-to-operate or time delay relay 21, having normally closed contacts 22 and 23, has its operating coil connected in parallel with the operating coil of relay 17. The solenoid 13, which is to be energized, may be connected in series with the A contacts of switches 15 across the alternating current supply 16, through the contacts 20 of relay 17. The operating coil of relay 17 may be connected across the alternating current source 16 through the B contacts of switches 15, and, upon energization, may temporarily lock operated over the contacts 18 of relay 17, the contacts 22 of relay 21, to one side of the A. C. source and over the contacts 23 of relay 21, and the contacts 19 of relay 17 to the other side of the A. C. source. The operating coil of relay 21 may be connected directly across the source of current 16 through the B contacts of switches 15.

In the operation of the circuit, assuming that it is desired to initiate a cycle of operation, the switches 15 are simultaneously moved to their B positions. This operation results in immediate energization of the operating coil of relay 17 and the operating coil of relay 21. The energization of the operating coil of relay 17 causes its contacts 18, 19 and 20 to be closed immediately, thereby completing a locking circuit from

one side of the source 16 through contacts 22, contacts 18, operating coil of relay 17, contacts 19 and contacts 23, back to the other side of the source 16. The operation of relay 17 also closes contacts 20, which results in the completion of a preparatory circuit to the solenoid 13. However, since the switches 15 are now in contact with their B contacts, no current will flow to the solenoid 13. At this time, the contacts 22 and 23 of relay 21 will not be opened since relay 21 has a definite time delay or slow-to-operate characteristic. With all of the contacts of both relays 17 and 21 now closed, the switches 15 are immediately moved to their A positions, which operation results in energization of the solenoid 13 through the closed contacts 20 of relay 17.

It is obvious, from the above description, that in order for an operator to initiate a cycle of operation of the machinery to be operated, it is not only necessary that he depress both switches 15, but also that he release both switches 15 almost immediately. Any delay in the release of the switches 15 will result in a failure of the circuit to operate since the time delay of relay 21 is made a very small value. Therefore, it will be seen that after the period of the time delay of relay 21 has run, the contacts 22 and 23 of the relay 21 will be opened, thus rendering the locking circuit inoperative; consequently, release at this time of switches 15 to their A positions will result in immediate release of relay 17, thereby immediately breaking the circuit to solenoid 13 at contacts 20.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A device for controlling the current to a load comprising a relay having an operating coil, a source of current, normally open contacts on said relay in series with said load, a delayed action electromagnetic device having an operating coil and having normally closed contacts controlled thereby, other normally open contacts on said relay in series with the operating coil of said relay and in series with and normally closed contacts on said time delay device, and a pair of switches associated with said source of current and simultaneously movable from a load energizing to a relay energizing position to energize said relay and time delay device and movable thereafter to said load energizing position to energize said load when the contacts of said relay are held closed by a current through the contacts of said time delay device.

2. A safety device for controlling current to a load comprising a source of current, a load device, a pair of separately actuatable two-position switches each having a contact at each position

and means to connect opposite sides of said current source to like contacts at either position, a relay having its operating coil connected across the second position contacts of said switches and having a first set of normally open contacts connected in series with said load device and the first position contacts of said switches, a slow to operate relay having its operating coil connected across the second position contacts of said switches, second and third sets of normally open contacts controlled by said first mentioned relay and connected in series with its operating coil, two sets of normally closed contacts controlled by said slow to operate relay connected in series with said second and third sets of normally open contacts and the operating coil of said first mentioned relay, each set of normally closed contacts being connected to different sides of said source of current, whereby connection of said current source across said second position contacts energizes the operating coils of said relays and effects immediate closure of all of said normally open contacts and causes said first mentioned relay to be locked operated for a time equivalent to the time delay characteristics of said slow to operate relay and subsequent simultaneous connection of said first position contacts across said source before operation of said slow to operate relay energizes said load device.

3. A safety device for energizing a load comprising a current source, a pair of single pole double throw switches having their movable elements connected to opposite sides of said source, a time delay device energizable from said source through simultaneous contact of said movable elements with first like poles of said switches, a relay having its operating coil connected in parallel with said time delay device, a first pair of normally open contacts controlled by said relay, a load device connected in series with said normally open contacts across second like poles of said switches, a locking circuit for said relay including contacts controlled by said relay effective to lock said relay operated upon energization of said relay operating coil, and contacts controlled by said time delay device effective to deenergize said relay after a predetermined short time interval determined by the time delay characteristic of said time delay device, whereby only simultaneous movement of said elements into contact with said second like poles before expiration of said predetermined time interval results in energization of said load device.
